UNITED STATES PATENT OFFICE

2,584,816

ELECTROPLATING CONTROL SYSTEM

Matthew L. Sands, Everett, Mass., assignor to the
United States of America as represented by the
United States Atomic Energy Commission

Application August 17, 1948, Serial No. 44,789

2 Claims. (Cl. 204—231)

1

This invention relates to an improvement in electroplating apparatus. More specifically the invention concerns a control system for maintaining constant the potential between the cathode and the plating solution in a plating cell.

Many electroplating operations require extreme constancy and accuracy of the cathode-to-solution potential. This potential may vary during ordinary operation of a plating cell. Such variations occur because of variations in such factors as the current density at either or both of the electrodes, the extent of polarization at the electrodes, and the ion concentration, purity, and temperature of the plating solution.

It is accordingly the principal object of this invention to provide an improved electroplating apparatus wherein the potential between the cathode and the plating solution is maintained constant despite changes in conditions which may occur during the plating operation.

For understanding of the invention, reference is made to the attached drawing. In the drawing, the single figure is a schematic diagram of an embodiment of the electroplating apparatus of the invention.

As shown in the drawing the plating cell 10 comprises a conventional anode 12 and cathode 14 disposed in a plating solution 16. A source of direct voltage 18 having a potential of, for example, 90 volts is connected in series with vacuum tube 24 acting as a variable resistance and the plating electrodes. In the connection between the positive terminal of the voltage source 18 and the anode 12 are a conventional switch 20 for starting and stopping the plating operation, and an ammeter 22 for indication of the value of the plating current. A voltmeter 26 is connected between the electrodes of the plating cell 10 to indicate the potential difference therebetween. It will be seen that except for the control tube 24 the system as thus far described constitutes conventional electroplating apparatus.

The plating solution 16 is connected by a salt bridge 30 to the reference cell 32. Preferably the reference cell 32 is a calomel cell, shown in conventionalized fashion in the drawing. For the purpose of this specification electrode 31 will be designated as the negative terminal. This negative terminal of the calomel cell 32 is connected to the input grid 34 of a direct voltage electronic amplifier comprising a balanced-pair input stage 36, a single-tube stage 38, and an output tube 24, the anode and cathode of which are connected between the positive terminal of the voltage source 18 and the anode 12 of the plating cell 10.

as described above. Thus any difference of potential between the cathode 14 of the plating cell and the negative terminal of the calomel cell 32 is impressed on the input of the amplifier 35. 5 The amplifier 35 need not be further described herein since the particular direct voltage amplifier circuit illustrated in the drawing does not in itself constitute the invention herein claimed, and since persons skilled in the art will readily design many appropriate amplifiers for the purposes herein described.

It will be seen that if at any time during operation of the plating cell the plating solution 16 should become less positive with respect to the cathode 14, the input grid 34 will become negative. This signal will be amplified and will appear as a positive signal on the grid 40 of the control tube 24. The voltage applied between the anode 12 and the cathode 14 will thus be increased, and the potential of the plating solution 16 will tend to be restored to its former value. Likewise, in similar fashion, if the plating solution 16 should become more positive with respect to the cathode 14, the amplifier control tube 24 10 would serve to reduce the potential between the electrodes of the plating cell 10 and thus again tend to restore the original potential between the cathode 14 and the plating solution 16. The system preferably includes means e. g. potentiometer 33 whereby adjustment of the potential between the cathode 14 and the plating solution 16 15 may be accomplished to any predetermined value. The system described is seen to possess the desirable feature that no current is drawn through the calomel cell. A voltmeter 42 measures the potential between the cathode 14 and the negative electrode of the calomel cell 32. The voltmeter 42 is preferably a vacuum tube voltmeter. 20 A suitable complement of parts and values of components are as follows:

Tubes 36 and 38	-----	Type 6Q7
Tube 24	-----	Type 6AK5
Resistors:		
45 11, 13, and 15	-----	K 300
17, 19, and 23	-----	meg 4
25 and 33	-----	meg 1
29, 30, and 37	-----	meg 3
41	-----	K wirewound 50
43	-----	ohm 200
50 Capacitors 45 and 47	-----	mfd .01

Persons skilled in the art will readily devise a large number of equivalents for the system above described, utilizing the teachings of the invention. It will be understood that the embodiment

3

shown in the drawing and described above is merely illustrative.

What is claimed is:

1. An electroplating system for maintaining the potential between a plating solution and plating electrode substantially constant, comprising an electroplating cell including a container for an electrolyte, an anode electrode and a cathode electrode immersed in the electrolyte; a first thermionic tube having at least a cathode, anode, and a grid; means electrically connecting the electroplating cell anode and cathode, a source of plating potential and the anode and cathode of the first thermionic tube in series; means for varying the resistance of the first thermionic tube in a direction to remove variations in potential between the electroplating cell cathode and the electrolyte comprising means for supplying a constant reference potential; a direct current electronic amplifier having at least a first grid controlled thermionic tube and means electrically connecting the grid-cathode space serially with said reference potential supply means, said electrolyte, and said electroplating cell cathode; means coupling the output of the electronic amplifier across the grid-cathode space of the said first thermionic tube with that polarity which increases the resistance thereof upon an increase in potential between the electroplating cell electrolyte and cathode and decreases the resistance thereof upon a decrease in potential between the electroplating cell, electrolyte and cathode, whereby tendencies to variation of potential between the electroplating cell electrolyte and cathode are inhibited.

2. An electroplating system having the characteristic of substantially constant potential between the electrolyte and cathode comprising an electroplating cell having a container for an electrolyte and an anode and cathode, and a grid controlled thermionic tube; means electrically connecting in series the electroplating cell anode, cathode and electrolyte with a source of plating potential and the anode-cathode interelectrode

space of said thermionic tube, means for varying the resistance of said thermionic tube in a direction to remove variations from a selected magnitude of the plating current comprising a cascade amplifier having a balanced amplifier stage and a voltage amplifier stage and reference potential supply means, said balanced amplifier comprising a first and a second grid controlled vacuum tube, means electrically connecting the cathodes of the 10 vacuum tubes together and to a common load resistor, means electrically connecting the grid-cathode interelectrode space of one of said balanced amplifier vacuum tubes in series with the reference potential supply means and with the electrolyte and cathode of the electroplating cell; selectable potential means connected in series with the grid-cathode interelectrode space of the other balanced amplifier vacuum tube to adjust the potential between the electroplating cell electrolyte and cathode to a selected magnitude; means electrically coupling the anode of the said other balanced amplifier vacuum tubes to the input of the voltage amplifier stage and means electrically coupling the output of the voltage amplifier stage to the grid of the grid controlled thermionic tube.
